UNITED STATES PATENT OFFICE.

WALTER H. AMBERGER, OF PHILADELPHIA, PENNSYLVANIA.

BUOY FOR SUBMARINES.

1,160,122.

Specification of Letters Patent. Patented Nov. 16, 1915.

Application filed June 1, 1915. Serial No. 31,473.

To all whom it may concern:

Be it known that I, WALTER H. AMBERGER, a citizen of the United States, residing at Philadelphia, in the county of Philadelphia and State of Pennsylvania, have invented certain new and useful Improvements in Buoys for Submarines, of which the following is a specification.

My invention relates to improvements in buoys for submarines, the object of the invention being to provide a buoy or buoys which is so connected with the submarine that in the event of accident to the latter which will prevent the submarine from rising to the surface, the buoy or buoys can be released and will float to the surface of the water, operating as a signal and also as a carrier for cables connected to the submarine, and by means of which the latter may be drawn to the surface.

A further object is to provide an improved construction of buoy for the purpose stated, and provide an improved means for inclosing or housing the buoy on the submarine.

A further object is to provide an improved arrangement of cables connected with the submarine and the buoy or buoys so as to provide ready means for drawing the submarine to the surface, and which will minimize any possibility of the cables fouling to interfere with the salvage of the boat.

With these and other objects in view, the invention consists in certain novel features of construction and combinations and arrangements of parts as will be more fully hereinafter described and pointed out in the claims.

In the accompanying drawings: Figure 1 is a view in elevation illustrating my improvements. Fig. 2 is a view in longitudinal section of my improved buoy. Fig. 3 is a view in longitudinal section showing the buoy in position in its casing on the submarine. Fig. 4 is an exaggerated view in longitudinal section showing the fragile covering for the torch end of the buoy. Fig. 5 is a detail view showing one of the metal brackets 3. Fig. 6 is an exaggerated view in section on the line 6—6 of Fig. 3. Fig. 7 is a top plan view of the submarine equipped with my improved buoys.

1 represents a submarine which is provided adjacent its opposite ends with metal straps 2 extending around the submarine,

and provided at opposite sides with metal brackets 3, one of these brackets being shown on an enlarged scale in Fig. 5.

4 represents my improved buoy which is shown in section in Fig. 2, in which view it will be noted that the buoy is of general cartridge shape having a horizontal partition 5 therein forming an upper chamber 6 which is rendered buoyant in any approved manner, preferably by providing a partial vacuum.

In the upper pointed end of the buoy I locate a torch 7 which comprises a metal casing 8 filled with a composition or material which will ignite when exposed to moisture.

Normally the material is tightly inclosed by a fragile cover 9 held over the end of the torch by a ring 10, and while I may of course provide various means for removing or tearing the cover 9, I have illustrated in Fig. 4 a simple means for this purpose.

11 is a bar which is located under the cover 9 and connected to a cord 12 which extends through the cover, and this cord is secured to the inner wall of the buoy casing 13 as shown in Fig. 3, so that when the buoy rises, it will promptly draw the bar 11 through the fragile cover 9 or else entirely remove the fragile cover so as to expose the composition to the moisture and cause the same to ignite.

As shown clearly in Figs. 1 and 2, I preferably employ two buoys 4, and provide for each buoy a casing 13 and as the buoys and casings are precisely alike, the description hereinafter will apply alike to both.

The casing 13 preferably extends entirely within the confines of the submarine so as to afford little or no resistance to the speed of the boat, and each casing is provided with a hinged cover 14 normally held in closed position by a turn button 15 operated by a crank shaft 16 extending into the boat.

17 is a screw which is mounted in brackets 18 and which at its upper end bears against a lug 19 on the free end of cover 14, so that by turning this screw in one direction, the cover can be elevated slightly to admit water to the casing 13, thereby equalizing the pressure on both sides of the cover, and allowing water to fill the casing 13 when the buoy 4 will promptly ascend, causing the tearing or removing of the fragile cover 11,

2
and elevating the hinged cover 14, so that the buoy will be free and can rise to the surface as shown in Fig. 1.

5 The space in each buoy 4 below partition 5 is divided by a longitudinal partition 20 into two compartments 21, each compartment containing a reel 22 and on the reels 22 the respective ends of a cable 23 are wound and secured.

10 The intermediate portions of the cables 23 are located longitudinally of the submarine as shown in Figs. 1 and 7, and are positioned through the brackets 3 so that when the buoy rises to the surface, both ends of 15 the cable can be reached to cause the elevation of the submarine, and lifting force is thereby equally applied to both ends of the submarine to raise the latter in a horizontal position. When both buoys rise to the surface, the salvage of the submarine is rendered 20 extremely easy because a hoist may be connected to both cables and exert a uniform pull at both sides and at both ends of the submarine. It is preferable to release 25 one buoy at a time to prevent fouling of the cables, and if for any reason one buoy does not work properly, the salvage of the boat can be accomplished through the single cable.

30 While the device might operate if the casings 13 were not water tight, I believe it a preferable arrangement to render the same water tight, and as it is necessary to extend the cables into the casings, I have recessed the cover as shown at 24, and provide packing material 25 in the recess to engage the cable.

35 It will be noted that with my improvements the buoys can be released from inside of the boat, and in the event that the submarine fails to rise to the surface when desired, the buoys can be released and will quickly rise to the surface, operating as signals to attract aid and supporting the cables in such position as to permit the submarine 40 to be readily raised to the surface.

45 While I have described my improvements in connection with a submarine for which it is especially adapted, yet I do not limit myself in that respect, as any boat may be so equipped.

50 It is to be understood that the buoys will carry relatively small cables, and by reason of their position they permit a heavier cable to be easily drawn through the brackets 3, the cable attached to the buoy acting as a messenger for the larger cable.

55 Various slight changes might be made in the general form and arrangement of parts described without departing from my invention, and hence I do not limit myself to the precise details set forth, but consider myself at liberty to make such changes and alterations as fairly fall within the spirit and scope of the appended claims.

60 Having thus described my invention, what I claim as new and desire to secure by Letters Patent is:

65 1. The combination with a boat having casings therein on top of the boat intermediate the ends thereof, and securing devices on both sides adjacent the ends of the boat, of buoys removably supported in the casings, each buoy having two reels and a cable, the intermediate portion of the cable 70 extending longitudinally of the boat and located in the securing devices on one side, and at its ends secured to the reels, substantially as described.

75 2. The combination with a boat having metal bands extending around the same adjacent the respective ends thereof, and metal loops fixed to the bands at both sides of the boat, of two buoys supported by the intermediate portion of the boat, each buoy having two reels, and a cable, the ends of which 80 are secured to the reels of the buoy, and the intermediate portion is located longitudinally of the boat and extending through the loops on the band, substantially as described.

85 90 In testimony whereof I have signed my name to this specification in the presence of two subscribing witnesses.

WALTER H. AMBERGER.
